UNITED STATES PATENT OFFICE

ALFRED DOYLE, OF HAMILTON, ONTARIO, CANADA

HOT AIR FURNACE

Application filed March 18, 1930. Serial No. 436,814.

My invention relates to improvements in hot air furnaces incorporating what are known as blowers or forced draft mechanisms, and the object of my invention is to utilize a portion of the air draft supplied to the furnace as a means for improving the air circulation through the furnace.

A further object of my invention is to provide for the injection of water into the blower conduit whereby the air passing therethrough vaporizes the water and becomes damp or humid. A portion of such humid air enters the furnace in the normal manner and the other portion enters the air circulating system around the furnace thus humidifying the heated air passing into the dwelling in which the furnace is contained.

My invention consists of a hot air furnace constructed and arranged all as hereinafter more particularly described and illustrated in the accompanying drawing in which.

The figure is a side elevational view of a furnace, blower mechanism and air circulating conduits, portions of such conduits being broken away.

My invention is capable of installation in any hot air furnace incorporating an artificial air draft mechanism, such as the blower 1 illustrated in the drawing. Blowers of this general type are finding increasing favor as they permit the use of coke or hard coal screenings in domestic furnaces. This class of a fuel which costs considerably less than the corresponding lump varieties, although containing approximately the same heating units is difficult to burn without the use of a forced draft, consequently necessitating the ever increasing use of blower mechanisms.

40 In the standard mechanism of this type such as illustrated, the blower 1 which consists of a fan in a casing, is actuated by means of an electrical motor 2 controlled by a thermostat 3, and the blower connected to the furnace underneath the fire box 4 by an air draft conduit 5.

In my invention I provide an air conduit 6 which extends from the conduit 5 to the cold air inlet pipe 7 which generally extends from a grating 8 in the floor of the

dwelling to the base 9 of the furnace casing 10. It being understood that the cold air descends the pipe 7 into the air chambers surrounding the furnace and passes from thence through the hot air pipes 11 back 55 into the dwelling. The number of cold air inlet pipes 7 and hot air pipes 11 being dependent upon the size of the furnace and the dwelling.

The upper end 12 of my conduit 6 is 60 turned downwardly into the centre of the cold air conduit 7, and is provided at its open end with a draft deflector cone 13 which is supported by a plurality of members 14 and spaced away from such open 65 end. The upper ends of the members 14 are secured to a collar 15 which is slidably mounted upon the end of the conduit so that the distance between the cone 13 and the open end of the conduit can be regulated. 70 A set screw 16 is furnished for securing the collar 15 in its adjusted position.

A water supply pipe 17 communicates with the air draft conduit 5 in the vicinity of the blower end thereof, being connected 75 to any suitable source of water supply, and furnished with a cock 18 for regulating the passage of water through the pipe 17 into the conduit 5. At the other end of the conduit, I provide a water sump and dirt 80 collector 19 to which is connected a water drain pipe 20 and a drainage cock 21. The pipe 20 extends into the sump intermediately of its depth so that any dirt collecting within the sump is withheld from passing 85 into the drain pipe. The cock 21 is furnished for draining the dirt or sediment out of the sump. For regulating the passage of air through the air draft conduit 5 into the furnace, I provide a butterfly valve 22 90 in the conduit adjacent to the furnace.

When the furnace is alight and the blower fan 1 actuating, the air enters the furnace through the cold air pipe 7 and upon being heated passes therefrom through the hot 95 air pipes 11 into the dwelling. The air draft passes from the blower 1 through the conduit 5 and into the furnace, the passage of air through the conduit 5 being regulated by the valve 22. A portion of the air draft 100

passing through the conduit 5 enters the conduit 6 and passes from thence into the cold air pipe 7, flowing in the same direction as the passage of cold air down the pipe 5 into the furnace. As the air draft is ejected from the end of the pipe 6, it strikes the cone 13 and in spreading creates a down draft in the cold air pipe 7. In this manner, the air passing down the cold air pipe 7 through the furnace and outlet pipes 11 is kept in constant circulation; so that all the rooms in the dwelling can be retained at an even temperature.

In supplying water to the conduit 5 through the pipe 7, I have provided means whereby the air entering the cold air pipe 7 through the conduit 6 is constantly damp, thus any desired humidity of the air passing through the furnace into the dwelling may be obtained, the amount of water introduced to the air current being regulated by the valve 18.

The introduction of water into the air conduit 5 cleans the air of any dust that it has accumulated in its passage through the dwelling, such damped dust collecting in the sump 19. The introduction of damped air into the combustion chamber of the furnace is also beneficial, in that the dampness settles the ash, thus keeping it from blowing about when the furnace is being cleaned out.

From the foregoing description it will be apparent that I have devised a particularly simple and efficient means for insuring a constant circulation of air through hot air furnaces, and also have provided means whereby such circulated air can be kept at any desired humidity. Although I have shown and described a particular embodiment of my invention, it is to be understood that I can make such changes and alterations as I may from time to time deem necessary, without departing from the spirit of my invention as set forth in the appended claims.

What I claim as my invention is:

1. In a forced draft hot air furnace of the character described, the combination with the forced air draft delivery conduit and the air circulation supply conduit to the furnace, of a third air conduit extending from the forced draft delivery conduit to the air circulation supply conduit, the end of the third conduit projecting into the centre of the air circulation supply conduit and extending in the same direction as the air flow in the air supply conduit, and means for spreading the air passing from the third conduit into the air supply conduit.

2. In a forced draft hot air furnace of the character described, the combination with the forced air draft delivery conduit and the air circulation supply conduit to the furnace, of a third air conduit extending from

the forced draft delivery conduit to the air circulation supply conduit, the end of the third conduit projecting into the centre of the air circulation supply conduit and extending in the same direction as the air flow in the air supply conduit, and a cone member positioned interiorly of the air supply conduit adjacent to the end of the third conduit for spreading the air passing from said third conduit into the air supply conduit. 75

3. In a forced draft hot air furnace of the character described, the combination with the forced air draft delivery conduit and the air circulation supply conduit to the furnace, of a third conduit extending from the forced draft delivery conduit to the air circulation supply conduit, the end of the third conduit projecting into the air circulation supply conduit and extending in the same direction as the air flow in said supply conduit, and a water injection member communicating with the forced draft delivery conduit at a point prior to the air draft entrance of the third conduit. 80 85
